ROTARY DRILLING RIG

Joseph Alexander Dunn, Los Angeles, Calif., assignor to The National Supply Company, Pittsburgh, Pa., a corporation of Pennsylvania

Application July 14, 1937, Serial No. 153,554

6 Claims. (Cl. 255—23)

This invention relates to drilling apparatus of the type employed in drilling oil, gas or water wells, or other holes in the earth's surface, and is particularly adaptable for use in the drilling of test holes as drilled in geophysical prospecting.

An object of this invention is to provide an improved form of drilling structure for the rotation of the drill string or pipe.

Another object of this invention is to provide drilling apparatus particularly applicable for the drilling of test holes as utilized in geophysical prospecting, which structure is of a portable character and includes a means for the automatic coupling or locking of a kelly in positive driving engagement with a drill stem.

Another object of this invention is to provide a drilling apparatus including a means providing an automatic connection between a swivel and a kelly and which means is capable of effecting the automatic coupling between the swivel and the kelly with the swivel moved to its highest operative position.

Another object of this invention is to provide an improved drill string drive connection which provides a stroke equal in length to the drill pipe sections and which is adaptable to use by an operator standing at or near the ground level without requiring an operator to climb the derrick in order that a section of the pipe may be added to the drill string.

Other objects and advantages of this invention it is believed will be apparent from the following detailed description of a preferred embodiment thereof as illustrated in the accompanying drawings.

In the drawings:

Figure 1 is an end elevation of a portable drilling apparatus embodying my invention illustrating a section of pipe about to be added to the drill string.

Figure 2 is a side elevation thereof and illustrating in dotted lines the position of the derrick when the apparatus is to be transported.

Figure 3 is an end elevation partly in section of a portion of the apparatus illustrating the relative position of the swivel and kelly after a section of pipe has been added and illustrating the kelly as elevated from the position illustrated in Figures 1 and 2.

Figure 4 is a side elevation partly in section of a portion of the apparatus illustrated in Figure 3 illustrating the same partially in vertical section.

Figure 5 is a view similar to Figure 4 but illus-

trating the kelly as moved into locked engagement with the swivel.

Figure 6 is a detached detail illustration of the preferred form of automatic coupling device embodied in my invention.

In the drawings the structure embodying my invention is illustrated as mounted upon a wheeled vehicle. Supported upon the frame 1 is a derrick 2 which is pivoted to the frame 1 at 3 to permit the derrick 2 to be lowered into the position illustrated in dotted lines in Figure 2 when the apparatus is being transported. Mounted upon the frame 1 is a spooling drum 4 upon which the line 5 is wound and which wire line is rove between the blocks 6 and 7 to support the swivel 8. The drill string 9 which is composed of a plurality of pipe sections secured together is normally supported by the swivel 8. A kelly 11 is provided and the kelly 11 has a bore large enough to permit the drill stem 9 and pipe couplings 12 thereof to pass freely through the bore of the kelly 11. Mounted upon the frame 1 is a rotary machine 13 which may be of any suitable or desirable construction as is well understood in the art and which rotary machine serves to rotate the kelly 11 in the customary or any desired manner.

Secured to the upper end of the kelly 11 is a bowl 14. Mounted upon the bowl 14 is an anti-friction bearing 15. Anti-friction bearing 15 is held in position by means of a ring 16 threaded to the bowl 14. The bearing 15 is positioned between the bowl 14 and a yoke 17 whereby the yoke 17 rotatably supports the kelly 11. The yoke 17 is provided with arms 18 which are secured to the cables 19 to enable the yoke 17 to be raised or lowered. The cables 19 pass over pulleys 21 mounted upon stub shafts 20 on the derrick 2. Secured to the arm 18 are chains 24, which chains 24 pass over sprockets 23. The sprockets 23 are fixed upon a drive shaft 22 so that a positive drive for the chains 24 is provided so that the yoke 17 can be either raised or lowered. The shaft 22 may be driven from any suitable or desirable source of power and is herein illustrated as being driven through a sprocket 25 from the chain driven from any suitable or desirable form of reversible drive means such as the reduction gear means illustrated at 26.

A clutch means, not illustrated, ordinarily provided in connection with such mechanism, is provided to enable the drive to the sprocket 25 to be released as desired.

The swivel 8 is preferably formed to include

a stationary stem 21 and a rotatable housing 28. The stem 21 is provided with a shoulder 29 upon which is mounted a thrust bearing 30 whereby housing 28 is rotatably supported upon the shoulder 29. A packing means 32 is provided between the housing 28 and the stem 21 to prevent entrance of drilling mud into the bearing 30.

Means are provided at the lower end of the housing 28 in the form of an adapter 33 to provide a rotary drive connection between the kelly 11 and the drill string 9.

Means are provided for effecting an automatic coupling or locking of the drive connection between the kelly 11 and drill string 9, which means preferably includes a pair of opposed laterally extending lugs 34 formed on the adapter 33 positioned to enter into slots 35 formed in the bowl 14.

The outer surface 36 of the adapter 33 is tapered to cooperate with the tapered seat 37 formed within the bowl 14 so that when the lugs 34 reach their operative driving position, the kelly 11 and swivel 8 are held in proper driving alignment.

In order to automatically effect the engagement of the locking means provided which is operative to avoid the necessity of an operator climbing the derrick 2 when it is desired to add a section of pipe, automatic locking means is provided which may include a spring-urged plunger 38 carried on the housing 28 of the swivel 8 in a fixed position with relation to the lugs 34 so that when the lugs 34 are in driving engagement in the slots 35, the plunger 38 is in position to enter one of the slots 35 and thus lock the lugs 34 in position. It will be obvious that the connection as thus provided is such that it can only be released by the lifting of the plunger 38 out of the slot entrance.

The adapter 33 is provided with internal threads 39 for engaging and supporting the drill string 9. Preferably a sub 40 is provided between the adapter 33 and drill string 9 so that the pipe sections are "made up" or "broken" upon the threads of the hub 40 to relieve wear from the adapter threads 39. The bowl 14 is provided with a shoulder 41 which acts as a limit stop to limit the downward travel of the kelly 11 through the rotary machine 13. With the kelly 11 and bowl 14 thus supported on the rotary 13, the plunger 38 can be raised, the lugs 34 backed out of the slots 35 to disengage the swivel from the kelly 11. The drill string 9 is then lifted a short distance by means of the blocks 6 and 7 and slips 42 are set in a tapered bore 31 to support the drill string 9. The swivel 8 is then disconnected from the drill string 9 preparatory to the adding of another section of pipe.

The operation of the improved drilling apparatus embodying my invention is as follows: Assuming the kelly 11 to be supported upon the rotary machine 13 and the drill string 9 to be supported by the slips 42 in the bowl 14 as illustrated in Figure 1; the swivel 8 is then lowered by paying off line 5 from the drum 4 and a new section of pipe is manually connected to the swivel sub 40 by an operator while standing upon the ground or at the ground level. The swivel 8 and the new section of pipe is then elevated to raise the new section of pipe over the drill string. The height of the derrick 2 is such that a pipe section of standard length will be conveniently handled in the manner as thus described. The lower end of the new pipe section is then connected to the upper end of the drill string 9.

The drill string 9 is then raised slightly to permit removal of the slips 42 whereby the total weight of the drill string is again supported by the blocks 6 and 7 and line 5 reeved thereon. As the drilling operation is again resumed, the mud pump customarily employed in such operation, but not illustrated, is started and the drilling mud is pumped down through the swivel 8 and drill string 9. The slot openings 35 in the bowl 14 are then oriented by an operator so that when the kelly 11 and bowl 14 are raised the lugs 34 will enter these slot openings. The power is then started to drive the shaft 22 whereby the yoke 17 and kelly 11 are raised. The kelly 11 is raised without rotation until the lugs 34 and the swivel adapter 33 enter the slots 35 of the bowl 14, which entering position is illustrated in Figure 4. The plunger 38 will be raised in this position and will ride upon the surface 43 of the bowl 14.

Upon starting of the rotary machine, the kelly 11 is revolved and upon being revolved, the plunger 38 drops into the slot opening 35, thereby preventing disengagement of the connection between the kelly 11 and drill string 9. This engagement is effected automatically upon the raising of the kelly 11 and upon starting of the rotation.

Frictional resistance provided by the swivel packing 32 and bearing 30 is sufficient to prevent rotation of the housing 28 and the lugs 34 under normal conditions until the plunger 38 has locked the kelly 11 and adapter 33 in positive driving relation. In order that the plunger 38 may be effectively moved into the locking position, a spring 44 is preferably interposed between the plunger 38 and the body 28 of the swivel 8. Operation of the rotary machine is then continued. Rotation of the kelly 11 is imparted to the adapter 33 and swivel 8 through the lugs 34. The drill string 9 is rotated through its threaded connection with the adapter 33. In the event that it is desired to add more weight to the drilling bit than is provided by the weight of the drill string 9, the yoke 17 can be used to apply a downward force through the driving of the drive shaft 22.

Having fully described my invention, it is to be understood that I do not wish to be limited to the details herein set forth, but my invention is of the full scope of the appended claims.

I claim:

1. In a rotary drilling device for rotating a drill string, the combination of a swivel to rotatably support said drill string, a kelly having a longitudinal bore through which a portion of said drill string extends, said kelly being provided at its upper end with a portion having a tapered seat formed therein, said swivel having a member provided at its lower end to effect a driving connection between the drill string and the kelly, said member having a complementary tapered portion adapted to register with the tapered seat of the kelly to align the swivel and kelly.

2. In a rotary swivel of the type used in the drilling of bore-holes, the combination of a stationary stem having an annular shoulder, an anti-friction thrust bearing on said shoulder, a rotatable housing surrounding said stem and bearing, a cap member supported on said bearing and detachably secured to said housing, an adapter secured to the lower end of said housing having threads to provide a driving connection with a drill pipe, and laterally extending lugs on said adapter to provide a driven connection with a kelly.

3. In a rotary swivel of the type used in the

drilling of bore-holes, the combination of a stationary stem having an annular shoulder, an anti-friction thrust bearing on said shoulder, a rotatable housing surrounding said stem and bearing, a cap member supported on said bearing and detachably secured to said housing, an adapter secured to the lower end of said housing having threads to provide a driving connection with a drill pipe, laterally extending lugs on said adapter to provide a driven connection with a kelly, and means including a spring-urged pin adapted to automatically lock the kelly to said housing upon predetermined relative movement therebetween.

4. In a rotary drilling device, the combination of a drive element, a swivel adapted to support said drive element, said swivel having an element operatively associated therewith and adapted to be removably secured to said drive element, cooperating means on said drive element and said 20 swivel element adapted to form a drive connection therebetween, said means including a lug on one of said elements adapted to enter a recess provided in the other of said elements, said connection being effected automatically upon relative longitudinal and rotary movement of the two 25

elements, a retrievable plunger on the lug-carrying element, and means to automatically project said plunger into said opening upon the connection being completed, whereby relative rotary movement of said elements is prevented.

5. In a well drilling device a rotary table, a carriage above said rotary table, a tubular kelly rotatably mounted in said carriage, said kelly having a central bore adapted to receive a drill stem, said bore tapering outwardly at the upper end thereof to provide a bowl-shaped cavity, a plurality of J-slots in the walls of said cavity, a drill stem in the bore of said kelly and a sub attached to said drill stem, said sub having projections thereon engaging said J-slots whereby a rigid connection is effected between the kelly and drill stem.

6. In a well drilling device, a tubular rotary shaft angular in cross section, a rotary table for driving said shaft, a drill rod within said shaft, J-slots in the walls of said shaft, a sub attached to said drill rod, and means on said sub for engaging said J-slots to impart rotation to said drill stem.

JOSEPH ALEXANDER DUNN.
